corporation of New York

Application November 27, 1946, Serial No. 712,585

10 Claims. (Cl. 250—49.5)

1

This invention relates to apparatus for the microanalysis of substances by means of X-ray excited photoelectrons.

An object of the invention is the provision of means for determining the constitution of a specimen by forming an electron optical image of electrons emitted by the different atoms of the specimen under excitation by X-rays.

It is known that when a substance is irradiated with X-rays, photoelectrons are emitted by the substance. It is furthermore known that the energy of the emitted electron will be that of the incident X-ray minus the energy necessary to expel the electron from the atom. The energy of the emitted photoelectron is thus characteristic for the emitting atom and a determination of the atomic constitution of a specimen is possible if the energy of the exciting photon, and the energy level from which the electron is extracted, are known.

It has been found that by irradiating a specimen with X-rays and subjecting the emitted photoelectrons to one or more focussing fields in an electron optical system, an enlarged electron image of the specimen, or a selected portion thereof, may be obtained which provides an image of the atomic constitution of the specimen. It is desirable to irradiate the specimen with an X-ray beam containing the highest possible concentration of substantially monochromatic X-rays. This can advantageously be effected by exciting a selected X-ray emitter (target) under conditions providing a predominant line spectrum with a relatively weak continuous background. By the use of suitable filters, preferably placed as close as possible to the specimen in order to obtain the highest possible amount of radiant energy, it is possible to substantially improve the monochromism of the irradiating beam. The filter material is selected to contain an element having a K-absorption limit at a slightly shorter wave-length than the K-line of the target. For example, with a molybdenum target, a suitable element for the filter is zirconium.

Preferably the space between the target and the specimen is cooled and the filter element advantageously can form a wall of the cooling chamber adjacent the specimen thereby preventing contact of the coolant with the specimen.

The invention will be more particularly described for the purpose of illustration with reference to the accompanying drawing in which:

Fig. 1 is a diagrammatic elevation of apparatus embodying the principles of the invention;

2

Fig. 2 is a fragmentary detail view in sectional elevation of the irradiating section of the apparatus; and

Fig. 3 is a fragmentary detail view in sectional elevation of a modified embodiment of the invention.

In Fig. 1, 10 is the X-ray cathode, with accelerating electrode 11. 12 is the target foil, 13 the filter foil and 14 the specimen. 15 is a magnetic objective which produces an enlarged image of the photoelectron emission pattern of the specimen at 16. A portion of this image may be further enlarged by magnetic image projector 17 forming a final image at 18 which may be 15 photographically recorded on film 19, or viewed on a fluorescent screen at the same position.

In the apparatus of Fig. 2, the target foil 12, for example, a molybdenum foil .005 inch in thickness and the thin zirconium filter foil 13, 20 form the upper and lower walls respectively of a cooling chamber through which coolant is circulated by means of inlet conduit 20 and outlet conduit 21.

The magnetic objective 15 comprises a coil 22, 25 iron enclosure 23, and a gap member 24 of nonferromagnetic material such as brass. In a plane beyond the coil an electron image is formed if current of suitable intensity is passed through the coil. The instrument may be focussed by calibrating the magnetic lens current with respect to various precalculated energies of the emitted photoelectrons, using electrons generated by a conventional electron gun, for example, to obtain electrons of various known energies for the calibration and using a fluorescent screen to determine the focussing. By observing the image of the electrons produced on the fluorescent screen, corresponding values of focussing currents can be established for the different electron energies by 35 measuring the accelerating voltage and the current flowing through the magnetic lens coil.

In this way a calibration table or curve is provided, from which the proper lens current can be ascertained for any precalculated value of emitted 40 photoelectrons.

If the element to be determined is unknown, the electron beam can be focussed by placing a Geiger-Müller counter or other radiation recording device at the plane of the photographic film, 50 and the counting rate determined for various magnet coil currents. The maximum counting rate will correspond to the proper focussing current.

In order to increase the intensity of the image 55 and at the same time to reduce the amount of

spherical aberration it is advantageous to accelerate the photoelectrons immediately after they are emitted from the specimen. This may be effectively accomplished by means of an electrostatic immersion lens as shown at 30 in Fig. 3. An electrostatic focussing lens 31 is also provided.

The accelerating voltages used for X-ray generation and for the acceleration of the photoelectrons may be obtained from the same power supply. Both electron accelerating systems may be connected in parallel to the power supply. In order to reduce the problem of insulation presented by the close spacing of the target and the specimen it is advantageous to connect the target to the specimen and to energize the apparatus by a potential divider, as shown in Fig. 3, whereby the target and the specimen are maintained at an intermediate potential between the cathode potential and the ground.

I claim:

1. An electron microanalyzer comprising means for directing a beam of substantially monochromatic X-rays upon a specimen to be analyzed, means for accelerating photoelectrons emitted from the specimen, and means for focussing the accelerated photoelectrons to form an electron image.

2. An electron microanalyzer comprising means for directing a beam of substantially monochromatic X-rays upon a specimen to be analyzed, and means providing a focussing field adjacent said specimen to focus photoelectrons emitted by the specimen into an electron image.

3. An electron microanalyzer comprising means for directing a beam of substantially monochromatic X-rays upon a specimen to be analyzed and an electron focussing electrode adjacent said specimen.

4. An electron microanalyzer comprising an electron gun, a target adapted to emit X-rays under electron bombardment from the electron gun, means for positioning a specimen to be analyzed in the path of X-rays generated by said target, and means providing a focussing field adjacent the specimen to focus photoelectrons emitted by the specimen into an electron image.

5. An electron microanalyzer comprising an electron gun, a target adapted to emit X-rays under electron bombardment from the electron gun, means for positioning a specimen to be analyzed in the path of X-rays generated by said target, a filter member in the path of the X-rays substantially impermeable to X-rays of lower wave-length than the K-emission of the target, and means providing an accelerating and focussing field adjacent the specimen to focus photoelectrons emitted by the specimen into an electron image.

6. An electron microanalyzer comprising an electron gun, a target adapted to emit X-rays under electron bombardment from the electron gun, means for positioning a specimen to be analyzed in the path of X-rays generated by said target, a filter member in the path of the X-rays substantially impermeable to X-rays of lower wave-length than the K-emission of the target, and means providing an accelerating and focussing field adjacent the specimen to focus photoelectrons emitted by the specimen into an electron image.

electron gun, a thin target foil of a metal adapted to emit X-rays under electron bombardment from the electron gun, means for positioning a specimen to be analyzed in the path of X-rays emitted by the target, a filter member between the target and the specimen substantially impermeable to X-rays of lower wave-length than the K-emission of the target, and means providing an accelerating and focussing field adjacent the specimen to focus photoelectrons emitted by the specimen into an electron image.

7. An electron microanalyzer comprising an electron gun, a thin target foil of a metal adapted to emit X-rays under electron bombardment from the electron gun, means for positioning a specimen to be analyzed in the path of X-rays emitted by the target, a filter member between the target and the specimen substantially impermeable to X-rays of lower wave-length than the K-emission of the target, means positioning the target foil and the filter member in spaced relation and cooperating therewith to define a chamber between the target foil and the filter member, means for passing a cooling medium through said chamber, and means providing an accelerating and focussing field adjacent the specimen to focus photoelectrons emitted by the specimen into an electron image.

8. An electron microanalyzer comprising an electron gun, a thin target foil of molybdenum positioned in the path of electrons from the electron gun, means for positioning a specimen to be analyzed in the path of X-rays emitted by the target, a thin filter foil of zirconium positioned between the target foil and the specimen, and means providing an accelerating and focussing field adjacent the specimen to focus photoelectrons emitted by the specimen into an electron image.

9. In an electron microanalyzer, a source of substantially monochromatic X-rays comprising a thin target foil of a metal adapted to emit X-rays under electron bombardment, a thin filter foil substantially impermeable to X-rays of lower wave-length than the K-emission of the target, means positioning the target foil and the filter foil in spaced relation and cooperating therewith to define a chamber between the target foil and the filter foil, and means for passing a cooling medium through said chamber.

10. In an electron microanalyzer, a source of substantially monochromatic X-rays comprising a thin target foil of molybdenum, a thin filter foil of zirconium, means positioning the target foil and the filter foil in spaced relation and cooperating therewith to define a chamber between the target foil and the filter foil, and means for passing a cooling medium through said chamber.
